UNITED STATES PATENT OFFICE.

WILLIAM E. WINE, OF TOLEDO, OHIO.

UNDERFRAME FOR RAILWAY-CARS.

1,188,028.

Specification of Letters Patent. Patented June 20, 1916.

Application filed August 23, 1915. Serial No. 46,885.

To all whom it may concern:

Be it known that I, WILLIAM E. WINE, a citizen of the United States, and a resident of Toledo, county of Lucas, and State of Ohio, have made and invented certain new and useful Improvements in Underframes for Railway-Cars, of which the following is a specification.

My invention relates to new and useful improvements in underframes for railway cars, and more particularly to a reinforcing and strengthening means that may be applied to the wooden center sills of freight cars to materially strengthen the same.

15 The tendency toward longer and heavier trains naturally increases the severe buffing and pulling stresses to which the cars are subjected, which often results in damaged cars, and it has become a common practice 20 to remove the wooden center sills to which the draft rigging is secured, and substitute therefor steel center sills or steel underframes at comparatively great expense.

The object of my invention is to provide 25 a novel construction adapted for use in the repair of wooden cars which have become damaged by buffing shocks or severe strains, or to apply directly to wooden cars which are in good condition but which would in 30 time become damaged by the strain which they are now subjected to.

Another object of my invention is to provide a reinforcing means that may be readily applied and which will only necessitate 35 the removal of the old wooden end sill, jacking the car body off of the bolsters and needle beams and inserting the reinforcing means longitudinally of the center sills.

Still another object of my invention is to 40 provide a reinforcing means that may be inserted between the wooden center sills and will produce a lower center of gravity of the section, which is greatly desired for two reasons, first, it brings the neutral axis of 45 the beam or member in line with the coupler horn for buffing, and second it reduces the eccentricity of the center line of the draft gear from the neutral axis.

Still another object of my invention is to 50 provide a reinforcing means that is made up entirely of standard commercial bars of steel or sections, and requires no special dies or machinery for its manufacture.

Still another object of my invention is to so join the sections that the rivets are located 55 approximately of the neutral axis of the member, thus not having to punch the rivet holes through that part of the beam which is subjected to the tensile or compression strain.

Still other objects of my invention are to provide a reinforcing means which is light in weight and providing a maximum of strength for a minimum amount of material used; to provide a reinforcing means that 65 will be neat in appearance and readily assembled and cheap to manufacture.

With these and other objects in view, my invention consists in certain new and novel constructions and combination of parts 70 which will be hereinafter more fully described and pointed out in the claims.

In the accompanying drawings: Figure 1 is a fragmentary top plan view of my improved reinforcing means; Fig. 2 is a side 75 elevation of the same; Fig. 3 is an end view; Fig. 4 is a sectional view taken on lines 4-4 of Fig. 1; Fig. 5 is a fragmentary top plan view of a slightly modified form; Fig. 6 is a side elevation of the same; Fig. 7 is an end 80 view of the same, and Fig. 8 is a sectional view taken on lines 8-8 of Fig. 5.

Referring now to the drawings, it will be seen that the reinforcing means is made up of four angle sections; two of the angles 1 85 and 2 formed with relatively long vertical legs or webs 3 and 4 and upper portions or flanges 5 and 6 which extend inwardly. Securely riveted to these web portions are the other angle members 7 and 8, the webs of 90 these angles 9 and 10 extending completely under the wooden center sills 9' and 10'. This reinforcing member is adapted to extend the entire length of the wooden center sills, and although only one end is shown, 95 it will be understood that the illustration and description of one end portion is a complete description and illustration of the remaining end portion.

By providing a wide bottom web which 100 extends completely across the bottom of the wooden center sills, two advantages are obtained, in that the web reinforces the old wooden sills laterally and also renders the application of the device to the car much 105 more simple, as the web will be provided

with holes that register with the bolts that already extend vertically through the wooden sills, thus doing away with the necessity of boring separate bolt holes through the said sills. Furthermore the distribution of the metal in the bottom webs lowers the center of gravity of the center sills, which as heretofore mentioned is greatly desired.

- 10 The draft arms 11 and 12 are securely riveted to the bottom webs 8 and 9, and the low center of gravity of the section by the use of the wide bottom webs brings the neutral axis of the beam member nearer in line 15 with the coupler horn for buffing. Secured to the ends of the angle members 1 and 2 are the reinforcing plates 13 and 14, which contact with the tie plate 15. Also at different points throughout the length of the reinforcing members are located separators 16, which are shown in dotted lines in Fig. 1, which separators may be of any desired shape or length and extend from the vertical flange of the bottom member on one side to 25 the vertical flange on the other side, and which separator may be solid or of stamped metal, the object being to additionally reinforce the angles and guard against the transverse strains of the center sills. These 30 separators 16 are securely riveted to the members mentioned, and as many rivets being used as desired. The separators that are used over the bolster are of course provided with a passageway for the admission of the 35 king pin.

Referring now to the modified form shown in Figs. 5 to 8 inclusive, it will be seen that in this instance slightly differently shaped angular members are used, as the 40 members 19 and 20 when assembled in this instance form a structure box-like in cross section. Also securely riveted to these members 19 and 20 are the sections 21 and 22 which extend transversely across the center 45 sills, but extend longitudinally of the center sills for only a portion of their length. The end plates 23 and 24 in this instance are secured to the inner sides of the members 19 and 20 in contradistinction to the 50 outer side as shown in Fig. 1. By providing angles of sufficient weight it is possible to reconstruct the wooden underframe of old cars and at the same time make them nearly as strong and substantial as an all-steel underframe one, and at the same time the expense 55 far less than an all-steel underframe.

From the foregoing it will be seen that the structure *per se* may be quickly and readily assembled, and that it may also be 60 applied to the wooden center sills at a relatively small labor expense. Furthermore the bottom webs are bolted to the center sills, it being possible to use the old bolts now in use, thus doing away with the expense of

drilling additional holes throughout the length of the center sills; furthermore, the lower center of gravity is obtained and the position of the rivets is such that the strength of the angles is not materially lessened.

Variations may be made without departing from the spirit of the invention.

Having thus described my invention, what I claim as new and desire to secure by Letters Patent is:—

1. A reinforcement for wooden underframe railway cars, comprising angle members adapted when placed in position to extend along the inner adjacent sides of the sills of the underframe, a second set of angle members the flanges of which are secured to the webs of the first mentioned angle members, and the webs of the second set of angle members extending outwardly, and means secured to the webs of said second set of angle members for the reception of a draft gear.

2. A reinforced wooden underframe for railway cars, comprising wooden center sills; angle members extending along the inner adjacent sides of said sills, a second set of angle members extending throughout the length of the wooden underframe the flanges of which are secured to the webs of the first mentioned angle members and the webs of the second set of angle members extending across the bottom of said center sills, said webs provided with a plurality of openings therein, so that the said webs of said angle members may be secured to the said center sills, and members secured to the webs of said second set of angle members for the reception of a draft gear.

3. A reinforced wooden underframe for railway cars comprising wooden center sills; angle bars extending along the inner adjacent sides of said sills and throughout their length, the flanges of said angle members extending inwardly, a second set of angle members extending the entire length of the said wooden center sills, the flanges of which are secured to the webs of the first mentioned angle members, the webs of the second set of said angle members extending across the bottom of said center sills and angular members secured to the webs of said second angle members for supporting a draft gear.

4. A reinforcement for railway cars having wooden center sills comprising angle members adapted to extend along the inner adjacent sides of said wooden sills and extending substantially throughout the length of said wooden sills, the flanges of said angle members extending toward each other, a second set of angle members the flanges of which are secured to the webs of the first mentioned angle members, and the webs of the second set of angle members adapted

to extend across the bottom of the said center sills, and a reinforcing means located between the said angle members and in a position that will be above the bolster when 5 said underframe is placed in its position.

5. A reinforcement for wooden railway cars comprising two angular members positioned to form a box-like structure in cross section, a second set of angular members 10 secured to the webs of the first mentioned angular members and the webs of the same extending outwardly, and angular members secured to the outwardly extending webs of said last mentioned angular members for 15 the reception of a draft gear.

6. A reinforcement for wooden under-frame railway cars comprising angular means adapted when placed in position to extend along the inner adjacent sides of the 20 sills of the underframe a set of angle members the flanges of which are secured to the said angular means and the webs of the said set of angle members extending outwardly and means secured to the webs of said set

of angle members for the reception of a 25 draft gear.

7. A reinforced wooden underframe for railway cars comprising wooden center sills, angular means extending along the inner adjacent sides of said sills and throughout 30 their length, portions of said angular means extending downwardly, a set of angle members extending substantially the entire length of the said wooden center sills, the flanges of which are secured to the downwardly extending portion of the said angular means, the webs of the said set of said angle members extending across the bottom of said center sills, and members secured 35 to the webs of said angle members for supporting a draft gear.

Signed at Washington, D. C., this 14th day of August, A. D. 1915.
